UNITED STATES PATENT OFFICE.

CARRIE FARMER, OF MERLIN, OREGON.

DARNING LAST.

Application filed April 21, 1922. Serial No. 555,817.

To all whom it may concern:

Be it known that I, CARRIE FARMER, a citizen of the United States, residing at Merlin, in the county of Josephine and State of 5 Oregon, have invented certain new and useful Improvements in Darning Lasts, of which the following is a specification.

My invention relates to darning-lasts for use in darning stockings or other like articles, and has for its objects to provide a last shaped similar to the human foot and being adjustable so as to be readily extended or retracted for fitting different sizes in stockings and the like.

15 Another important object of the invention is to provide a device of this nature which is easily assembled and disassembled.

A still further object of the invention is to provide a darning-last of this nature 20 which is extremely simple and efficient in construction, reliable in operation, comparatively inexpensive to manufacture, and well adapted to the purpose for which it is designed.

25 With the above and numerous other objects in view as will appear as the description progresses, the invention resides in certain novel features of construction, and the combination and arrangement of parts as 30 will be hereinafter more fully described and claimed.

In the drawing:—

Figure 1 is a side elevation of the darning-last,

35 Figure 2 is a top plan thereof,

Figure 3 is a perspective of the toe and instep forming member,

Figure 4 is a perspective of the extension thereof,

40 Figure 5 is a perspective of the U-shaped edge plate, and

Figure 6 is a perspective of the bottom plate.

Referring to the drawing in detail it will 45 be seen that the heel casing 1 has an ankle extension 2 attached thereto at its upper edge by a rivet 3, the head of which is rounded so as not to tear or injure any fabric coming into contact therewith. A sole or 50 bottom plate 4 is provided at its heel end with a curved peripheral flange 5 having a plurality of apertures 6 therein whereby the rivets 7 may be passed therethrough and engaged with the bottom edge of the heel

casing 1. A sole extension plate 9 is constructed with an elongated longitudinally extending slot 10 communicating at one edge with a plurality of bayonet slots 11 which are adapted to be engaged with the rivet 12 carried at the forward end of the sole plate 60 4. Thus it will be seen that the auxiliary sole plate 9 may be adjusted longitudinally of the sole plate 4 for fitting different lengths in the foot portion of socks or stockings with which it is desired to use the device. At the 65 forward end of the auxiliary sole plate 9 there is situated a toe shield 14 having an instep extension 15 formed thereon. A rivet 16 is mounted on the under face of the instep extension 15 adjacent its end. An auxiliary 70 instep member 17 is provided with an elongated slot 18 extending longitudinally thereof and communicating with a plurality of bayonet slots 19 which are adapted to receive the rivet 16 whereby it will be seen 75 that the instep members 15 and 17 are adjustable in relation to each other. The auxiliary instep member 17 is provided at one end with a yoke 20 for cooperating with the ankle casing 2. The terminals of the yoke member 20 have situated thereon the rivets 21. An elongated slot 22 is provided on each side of the ankle casing 2 extending longitudinally with and adjacent to its upper edge and this slot 21 communicates with a 80 plurality of bayonet slots 23 adapted to receive the rivets 21 so that the yoke 20 may be adjusted in relation to the ankle casing 2 85 as will be readily understood by an inspection of Figure 1.

90 The toe shield 14 has situated thereon a rivet 25 so that the U-shaped edge plate 26 may be attached thereto, this rivet 25 passing through the centrally located aperture 27. The legs of the U-shaped edge 95 plate 26 are each provided with an elongated longitudinally extending slot 29 which communicates with a plurality of bayonet slots 30 that are adapted to receive rivets 31 carried at the forward ends of the heel casing 1. 100

From the above description, it will be readily seen that a darning-last has been provided that is adjustable as to its various parts so that the size of the last may be varied to conform to the size and shape of the foot portion of a stocking or the like. Although I have described my invention with some degree of particularity, it is 105

to be understood that the modification shown has been disclosed merely by way of example and that numerous changes in the form and in the combination and arrangement of parts may be resorted to without departing from the spirit of the invention as hereinafter claimed.

Having thus described my invention what I claim as new is:—

- 10 1. A darning-last of the class described comprising a heel casing member, a sole plate attached thereto, a sole plate extension adjustably mounted on the sole plate, a toe shield formed on the sole plate extension, an instep extension formed on the toe shield, an auxiliary instep member adjustably connected to the instep extension, a yoke formed thereon, and an ankle casing mounted on the heel casing and adjustably connected to the 20 said yoke.
- 15 2. A darning-last of the class described comprising a heel casing member, a sole plate attached thereto, a sole plate extension adjustably mounted on the sole plate, a toe shield formed on the sole plate extension, an instep extension formed on the toe shield, an auxiliary instep member adjustably connected to the instep extension, a yoke formed thereon, and an ankle casing mounted on the 25 heel casing and adjustably connected to the said yoke, a U-shaped edge plate fixed inter-

mediate its ends to the toe shield and adjustably connected to the heel casing.

3. A darning last of the class described comprising a heel casing member, a longitudinally adjustable sole plate attached thereto, a toe shield formed on the sole plate, a longitudinally adjustable instep extension formed on the toe shield, and an ankle casing mounted on the heel casing and connected with one end of said instep extension. 40

4. A darning last of the class described comprising a heel casing member, a longitudinally adjustable sole plate attached thereto, a toe shield formed on the sole plate, a longitudinally adjustable instep extension formed on the toe shield. 45

5. A darning last of the class described comprising a heel casing member, a longitudinally adjustable sole plate attached thereto, a toe shield formed on the sole plate, an adjustable instep extension formed on the toe plate, and a U-shaped edge plate fixed to the toe plate and adjustably connected to the heel casing. 50

In testimony whereof I affix my signature in presence of two witnesses.

Mrs. CARRIE FARMER.
